OVER-KNEE-LENGTH STOCKING WITH
ROLLING-FRONT GARTER BANDClaude Shelton, Reading, Pa., assignor to Vanity
Fair Silk Mills, Reading, Pa., a corporation of
Pennsylvania

Application June 1, 1938, Serial No. 211,294

10 Claims. (Cl. 2—239)

This invention relates to knit hosiery of the over-knee-length type and has for its object the provision of a stocking having a circumferential garter band adjacent the top which functions as a strain absorber with reference to stresses produced by flexions of the knee, and as a wrinkle preventer and remover, by rolling down upon itself in the front responsive to stresses produced by flexing the knee, and returning to normal position as the stresses disappear.

Other objects of the invention will appear as the following description of a preferred embodiment thereof proceeds.

In the drawing throughout the several figures of which the same characters of reference have been employed to designate identical parts:

Figure 1 is a perspective view of a stocking embodying the principles of the present invention;

Figure 2 is a perspective view of the same stocking with the knee bent;

Figure 3 is a section of Figure 2;

Figure 4 is a perspective view of the upper end of the stocking from the rear;

Figure 5 is a diametrical cross section taken in a plane which intersects one of the stays;

Figure 6 is a diagrammatic view illustrating a woven garter band knit to the top of the stocking; and

Figure 7 is a perspective view illustrating a slightly modified form of the invention.

Referring now in detail to the several figures the numeral 1 represents a women's over-knee-length knit stocking having the elastic circumferential garter band 2 either integrally knit or otherwise secured to the top edge 3 of the stocking. The garter band preferably contains rubber elastic elements and is stretchable at least in a circumferential direction and preferably in both directions.

Figure 6 shows the band 2 of woven material having the elastic threads 13 and being knit or looped as at 14 to the basic fabric of the stocking.

The webbing which constitutes the garter band may be of any type, either woven, knitted or braided. The garter band 2 is worn turned down on the inside of the stocking. As the function of the garter band is to roll down upon itself in the front under the pull of the front portion of the stocking, it is essential that the garter band shall fit the leg tightly enough to hold its position without slipping, also that the stocking shall be secured to the garter band at the top edge of the latter.

Figure 5 shows that the elastic garter band 2 when in relaxed or repose condition is made of slightly smaller circumference at the lower or free edge than at the upper edge. This serves two functions, it causes the lower portion of the garter band to grip the leg particularly under

the downward thrust of the garter band against the leg produced by the pull of the stocking and it minimizes the constrictive pressure of the upper edge portion of the garter band against the leg permitting the front portion to readily draw away from the leg under the pull of the stocking, initiating the rolling.

Preferably, the stocking 1 is of the type having an integrally knit strain absorbing zone 4 incorporating one or more bands 5 of covered latex rubber thread stretchable longitudinally for absorbing at least a part of the strain produced by the flexion of the knee. Where such strain absorbing zone is present, the rolling front of the garter band of the present invention may be regarded as auxiliary to the strain absorbing zone.

In the illustrated embodiment of the invention a pair of stays or bones 6 are shown secured transversely of the garter band and preferably housed within pockets 7 integral with or sewn to said garter band. Said bones are preferably symmetrically positioned on either side of the median front line of the stocking and being closer than 180 degrees apart. These stays have the function of keeping the garter band its full width throughout the large arc at the sides and back of the stocking so that the entire rolling must be in the relative small arc on the front of the stocking between the stays. The stays have the further purpose of causing the webbing to come back more readily around the leg.

In operation, when the knee is flexed as illustrated in Figures 2 and 3, the pull induced by the stretching of the knee of the stocking first widens the strain absorbing zone 4 through stretching the rubber elastic components thereof and to the extent that the strain absorbing zone is inadequate to absorb the entire strain, the front portion of the garter band is rolled forward upon itself throughout an arcuate extent limited by the stays 6.

Figure 3 shows that the lower edge 8 of the garter band is in firm constrictive contact with the leg, but that the upper front portion of the garter band has been drawn out in a lip 9, the outer edge 10 of which is drawn downwardly, forming the roll, by the direct pull of that part 11 of the stocking which overlies the garter band. Due to the fact that the garter band is stretchable at least circumferentially and that the points of suspension of the curve of deflection 12 are relatively close together, the garter band immediately springs back to its normal position just as soon as the stress of the upper front portion of the stocking is relieved. This upward return of the front of the garter band to normal position draws out any wrinkles which otherwise would have remained in the knee of the stocking.

It will be understood to those skilled in the art that the garter band 2 may be attached by a top

ping, looping or seaming operation as well as by being integrally knit as has hereinbefore been suggested that the stocking itself can be made either with or without the strain absorbing zone

5 4. In that form of the invention shown in Figure 7, the strain absorbing zone has been reduced to a mere single narrow band of integrally knit covered latex rubber courses.

While I have in the above description disclosed 10 what I believe to be a preferred and practical embodiment of the invention, it will be understood to those skilled in the art that numerous equivalent constructions and arrangements of parts may be employed and still be within the 15 scope of the appended claims.

What I claim is:

1. Over-knee-length knit stocking having an elastic garter band above the knee, inwardly of the stocking, and connected thereto at the top of the garter band, stiff stays extending transversely of the garter band on opposite sides of the front center of said band said band being characterized by the absence of front stays, the lower edge of said band being free from attachment to said stocking at least between said stays.

2. Over-knee-length knit stocking having an elastic garter band above the knee, inwardly of the stocking, and connected thereto at the top of the garter band, said garter band incorporating rubber threads, stiff stays extending transversely of said garter band on opposite sides of the front center of the garter band said band being characterized by the absence of front stays, the lower edge of said band being free from attaching to said stocking at least between said stays.

3. Over-knee-length knit stocking having an elastic garter band above the knee, inwardly of the stocking and connected thereto at the top of said garter band, said garter band incorporating rubber threads so disposed as to impart elasticity to said band both circumferentially and widthwise, stiff stays extending transversely of said garter band on opposite sides of the front center of said band said band being characterized by the absence of front stays, the lower edge of said band being free from attachment to said stocking at least between said stays.

4. Over-knee-length knit stocking having an elastic garter band above the knee, inwardly of the stocking and connected thereto at the top of said garter band, the lower edge of said garter band being of smaller circumference than the upper edge when said band is in relaxed condition, whereby the lower edge is adapted to embrace the wearer's leg more snugly than the upper edge, stiff stays extending transversely of said garter band on opposite sides of the front center of said band said band being characterized by the absence of front stays, the lower edge of said band being free from attachment to said stocking at least between said stays.

5. Over-knee-length knit stocking having an elastic garter band above the knee, inwardly of the stocking and connected thereto at the top of the garter band, said garter band incorporating rubber threads so disposed as to impart elasticity both circumferentially and width-wise of said band, stiff stays extending transversely of said garter band on opposite sides of the front center of said band said band being characterized by the absence of front stays, the lower edge of said band being free from attachment to said stocking at least between said stays, and being of smaller circumference than the upper edge when the

band is in relaxed condition, whereby the lower edge is adapted to embrace the wearer's leg more snugly than the upper edge.

6. Over-knee-length knit stocking having an elastic garter band above the knee, inwardly of the stocking and connected thereto at the top of the garter band, stiff stays extending transversely of said band on opposite sides of the front center of said band said band being characterized by the absence of front stays, the lower edge of said band being free from attachment to said stocking at least between said stays, said stocking having a strain absorbing zone between the knee and said garter band.

7. Over-knee-length knit stocking having an elastic garter band above the knee, inwardly of the stocking and connected thereto at the top of said garter band said band being characterized by the absence of front stays, stiff stays extending transversely of said garter band on opposite sides of the front center of said band, the lower edge of said band being of smaller circumference than the upper edge when the band is in relaxed condition, whereby the lower edge is adapted to embrace the wearer's leg more snugly than the upper edge, said lower edge being free from attachment to said stocking at least between said stays.

8. Over-knee-length knit stocking having an elastic garter band above the knee, inwardly of the stocking and connected thereto at the top of the garter band, said band incorporating rubber threads, stiff stays extending transversely of said garter band on opposite sides of the front center of said band said band being characterized by the absence of front stays, the lower edge of said band being of smaller circumference than the upper edge when said band is in relaxed condition, whereby the lower edge is adapted to embrace the wearer's leg more snugly than the upper edge, said lower edge being free from attachment to said stocking at least between said stays.

9. Over-knee-length knit stocking having an elastic garter band above the knee, inwardly of the stocking and connected thereto at the top of the garter band, said band incorporating rubber threads so disposed as to impart elasticity to said band both circumferentially and widthwise, stiff stays extending transversely of said garter band on opposite sides of the front center of said band said band being characterized by the absence of front stays, the lower edge of said band being of smaller circumference than the upper edge when said band is in relaxed condition, whereby the lower edge is adapted to embrace the wearer's leg more snugly than the upper edge, said lower edge being free from attachment to said stocking at least between said stays.

10. Over-knee-length knit stocking, having an elastic garter band above the knee, inwardly of the stocking and connected thereto at the top of the garter band, said garter band incorporating rubber threads, stiff stays extending transversely of said garter band on opposite sides of the front center of said band, said band being characterized by the absence of front stays, the lower edge of said band being free from attachment to said stocking at least between said stays, and being of smaller circumference than the upper edge when the band is in relaxed condition, whereby the lower edge is adapted to embrace the wearer's leg more snugly than the upper edge.
